UNITED STATES PATENT OFFICE.

JOHN A. CUMLA AND ANDERS P. FRIDSTRÖM, OF EVERETT, MASSACHUSETTS; SAID FRIDSTRÖM ASSIGNOR TO SAID CUMLA.

SOFA-BED.

SPECIFICATION forming part of Letters Patent No. 795,199, dated July 18, 1905.

Application filed February 16, 1904. Renewed January 7, 1905. Serial No. 240,086.

To all whom it may concern:

Be it known that we, JOHN A. CUMLA, a citizen of the United States, and ANDERS P. FRIDSTRÖM, a citizen of Sweden, both residents of 5 Everett, in the county of Middlesex and State of Massachusetts, have jointly invented certain new and useful Improvements in Sofa-Beds, of which the following is a specification.

This invention relates to improvements in 10 sofa-beds adapted for use interchangeably as a bed or sofa, as occasions may require, and it is carried out as follows, reference being had to the accompanying drawings, wherein—

Figure 1 is a top plan view of the invention shown in position as a bed. Fig. 2 is a cross-section on the line 2 2 shown in Fig. 1. Fig. 3 is a cross-section on the line 3 3 in Fig. 1, showing the back swung upward to the position of a sofa. Fig. 4 is a cross-section on 20 the line 4 4 in Fig. 1, showing the back swung upward to the position of a sofa; and Fig. 5 is a cross-section on the line 5 5 in Fig. 1, showing the back swung upward in the position of a sofa.

25 Similar letters refer to similar parts wherever they occur on the different parts of the drawings.

In the drawings, A A represent the front legs, and A' A' are the rear legs, in a sofa-bed, as usual. In practice said legs are made of tubular metal, and to the upper ends thereof are secured, respectively, the heads or 30 couplings B B and B' B', as shown.

To the upper ends of the legs A A is suitably secured the front bar or rail C, and to the upper ends of the respective legs A A' A' are suitably secured the end bars or rails D D, which together constitute the seat-frame, to which the spring-mattress E of any 40 well-known form or construction is secured.

F F are the seat ends, secured to the seat-frame, as usual.

C' is a brace or stay secured to the front legs A A, and D' D' are stays or braces secured to the legs A A' A' in any suitable or well-known manner.

To the rear legs A' A' is secured a bar G at a suitable distance below the end bars D D, as shown.

50 G' is a brace secured to and connecting the

rear legs A' A' in any suitable or well-known manner.

H is the back-frame, which serves as the back-support when the device is used as a sofa, as shown in Fig. 3. Said frame H is 55 pivoted in its lower ends at h h to the couplings B' B' or to any other suitable part of the rear legs A' A', as may be most practical or convenient. In practice we provide the frame H with suitable end wings H' H' of 60 any desirable shape or size.

I is a spring-mattress secured to the frame H, as usual.

To the inner ends of the back-frame H are secured or made integral therewith ears or 65 projections H'' H'', to which are pivoted at h'' h'' the screw-threaded rods K K, the forward ends of which are guided in brackets d d, secured to the end rails D D, as shown.

To the forward ends of the rods K K is secured a longitudinal bar k, upon which rests loosely the forward end of a transverse bar L, the rear end of which is pivotally connected to the rear bar G, as shown in Fig. 2.

To the sides of the pivoted back-frame H is 75 pivoted at m m a L-shaped frame composed of vertical portions M M and a horizontal bar M'. The said L-shaped frame M M M' serves as a support for the swinging back H when the latter is swung into a horizontal position to be used as a bed, as represented in Figs. 1 and 2.

To the ends of the rear bar G are secured preferably curved or inclined rest-blocks g g, upon which the lower end M' of the pivoted 85 frame M M is caused to rest when the back-frame H is swung into vertical position for use as a sofa, as shown in Figs. 3 and 5, and while in such position the end M' of the frame M M comes to a stop against abutments or 90 stop projections g' g' on the blocks g g, as represented in Figs. 3 and 5, thus preventing the said frame H from being swung forward beyond a vertical, or nearly so, position when in use as a sofa.

When it is desired to swing 95 the back-frame H from the sofa position (shown in Figs. 3 and 5) to the bed position, (shown in Figs. 1 and 2,) the operator pulls on a knob Q, attached to a cord q, which passes loosely through a guide or eye C' on the 100

under side of the front rail C. The said cord passes around the under side of a pulley O, journaled on the rear lower brace G', and the upper end of said cord is suitably attached to an inwardly-projecting arm m' on the horizontal portion M' of the swinging frame M after passing loosely around the rear upper bar G, or a sleeve G'', as shown in Figs. 1, 2, and 4. By pulling on the cord q the swinging frame M is caused to swing backward sufficiently to cause the lower end M' thereof to be released from the rest-blocks g when the back-frame H is free to swing by gravity to the bed position (shown in Figs. 1 and 2) when the lower end M' of the frame M M is caused to rest on the floor, as shown in said Figs. 1 and 2.

For the purpose of gradually arresting the descent of the frame H we interpose between the stationary rear bar G and the movable bar h a pair of expansive coiled springs P P, as shown in Figs. 1, 2, 3, and 5. Said springs also serve the purpose of aiding in swinging the back H from the horizontal to its vertical position when released. In addition to such expansive springs P P we prefer to employ preferably compressible spiral cushion-springs K' K', arranged upon the rods K K, between the brackets d d and adjustable nuts K'' K'' on said rods K K, as shown in Figs. 1, 2, 3, and 5, by the compression of which the descent of the back-frame H is gradually arrested, so as to prevent concussion when the end M' of the frame M M reaches the floor. By adjusting the positions of the nuts K'' K'' on the rods K K the yielding resistance of the springs K' K' may be adjusted according to the weight of the back-frame of the sofa and its connected parts. Upon the under side of the forward end of the pivoted bar L is a tooth or projection l , adapted to engage the rear side of the movable bar h when the frame H is swung to bed position, (shown in Figs. 1 and 2,) thus preventing the back from being raised until said toothed bar L is released from the bar L.

For the purpose of readily raising the frame H from the bed position (shown in Figs. 1 and 2) to the sofa position (shown in Figs. 3 and 5) we use a knob n, attached to a cord N, passing loosely through the guide-eye C'' on the front rail C and below a lateral projection l' on the pivoted releasing-bar L, as shown in Figs. 1, 2, and 4. The said cord N is guided over the sleeve G'' on the bar G and attached at its rear end to the projection m' on the bar M', as shown in Figs. 1, 2, and 4. In raising the frame H from the bed position to the sofa position it is only necessary to pull on the knob n, which causes the cord N when tightened to raise the lock-bar L by contacting the side projection l' sufficiently to disengage the tooth l on said bar L from the longitudinal bar h , and by continuing to pull on the knob n of the cord N the frame H is raised into a

vertical, or nearly so, position, as indicated in Figs. 2, 3, and 5, causing the lower ends of the pivoted frame M M to come to a rest and locked positions relative to the blocks g on the bar G, as shown in Figs. 3 and 5, in which locked position the frame H cannot be released until the knob Q is pulled for releasing the ends of the pivoted frame M M from the rest-blocks g as herein above described.

For the purpose of properly guiding the swing-bar M' during the adjustment from a sofa to a bed, and vice versa, we interpose between the rear brace or stay G' and the swinging bar M' a connecting mechanism, as follows: To the brace or stay G' is pivotally connected a curved rod or bar R, having a slotted perforation r at its upper end adapted to receive a pin S, attached to a bracket T, secured to the swinging bar M', as shown in Figs. 1, 2, and 4.

What we desire to secure by Letters Patent and claim is—

1. In a sofa-bed, a seat and back pivotally connected, the back having pivoted to it a locking and supporting device, in combination rods pivotally connected to extensions or ears on the back, and movable in guides attached to the seat-frame, a horizontal bar attached to said rods, coiled springs connecting said bar to the rear of the seat-frame and a locking-bar pivotally connected to the rear of the seat-frame and engaging said bar when the back is swung into bed position substantially as described.

2. In a sofa-bed, a seat and back pivotally connected, a yielding frame pivotally connected to extensions on the back, a locking-bar pivotally connected to the bed-frame and adapted to engage said yielding frame when the device is used as a bed, and a raising device consisting of a cord-pull adapted to disengage the locking-bar and having its rear end attached to a frame pivotally connected to the back and a slotted guide-link pivotally connected to said frame and to a brace or stay on the bed-frame substantially as described and for the purpose set forth.

3. In a sofa-bed, a seat and back pivotally connected and a releasing device for lowering the back into horizontal position consisting of a cord-pull having its rear end attached to a projection on a locking and supporting frame pivotally connected to the back, and a guide or pulley intermediate the front and rear ends of said cord-pull on which the cord is guided during the release of said back from the seat-frame substantially as herein set forth.

In testimony whereof we have affixed our signatures in presence of two witnesses.

JOHN A. CUMLA.
ANDERS P. FRIDSTRÖM.
